Primary Examiner — Kelley Donnelly(74) *Attorney, Agent, or Firm* — David E. Eramian; Edward J. Baba; Bozicevic, Field & Francis LLP(57) **CLAIM**

The ornamental design for the dish plate grip, as shown and described.

DESCRIPTION

FIG. 1 is a perspective view of a dish plate grip of the present invention showing the new design;

FIG. 2 is a top view thereof;

FIG. 3 is a side view thereof;

FIG. 4 is a bottom view thereof; and,

FIG. 5 is a bottom perspective view thereof.

The broken line showing is included for the purpose of illustrating environment of the design and forms no part of the claimed design.
